UNITED STATES PATENT OFFICE.

JARED MARIS, OF COLUMBUS, OHIO.

DESIGN FOR THE ORNAMENTATION OF HUBS.

SPECIFICATION forming part of Design No. 16,467, dated January 12, 1886.

Application filed November 28, 1885. Serial No. 184,223. Term of patent 11 years.

To all whom it may concern:

Be it known that I, JARED MARIS, a citizen of the United States, residing at Columbus, in the county of Franklin and State of Ohio, have invented and produced a new and original Design for the Flange of Wheel-Hubs, of which the following is a specification, reference being had to the accompanying drawings, in which—

10. Figure 1 represents a view in end elevation of a hub-flange embodying my design, and Fig. 2 a plan view of the same.

My invention relates to a design for the ornamentation of the flange for a wheel-hub; and 15. it consists in a series of widely-separated depressions, each of which is made up of a series of reverse curves on the periphery of the flange, the intermediate portions of the periphery of the flange being curved in the arc of a circle 20 concentric with the center of the flange or hub.

A represents a hub-band, B the flange, and C the depressions in the periphery of the flange. These depressions, which are made

up of reverse curves, are separated from one 25 another, and the intermediate portions, *a*, of the periphery of the flange are in the arc of a circle concentric with the center of the flange or hub.

I would have it understood that I do not 30 restrict myself to any particular number of depressions, but consider myself at liberty to vary the number, if desired.

Having fully described my invention, what I claim as new, and desire to secure by Letters Patent, is—

In a design for hubs, the ornamentation of the same, consisting in a series of depressions in the periphery of the hub-flange, the portions of the periphery of the flange between 40 the depressions being in the arc of a circle concentric with the center of the flange, as shown and described.

JARED MARIS.
